UNITED STATES PATENT OFFICE.

AUDLEY H. STOW, OF THACKER, WEST VIRGINIA.

REVOLVING FIREARM.

SPECIFICATION forming part of Letters Patent No. 689,995, dated December 31, 1901.

Application filed December 13, 1900. Serial No. 39,759. (No model.)

To all whom it may concern:

Be it known that I, AUDLEY H. STOW, a citizen of the United States, residing at Thacker, in the county of Mingo and State of West Virginia, have invented a new and useful Improvement in Revolving Firearms, of which the following is a specification.

My invention relates to that class of revolving firearms in which a many-chambered cylinder is made to revolve at the rear of the barrel, particularly revolvers of the breakdown class; and the objects of my invention are, first, to provide a breakdown revolver which is less liable to be injured by rough usage, with a minimum weight of metal, and, secondly, to provide a breakdown revolver in which the barrel may be readily and with certainty unlocked by the revolver hand alone. I attain these objects by the mechanism illustrated in the accompanying drawings, in which—

Figure 1 is a side view of barrel and barrel-catch; Fig. 2, a view in perspective of catch-posts; Fig. 3, a side view of revolver-frame; Fig. 4, a rear view of another form of barrel-catch; Fig. 5, a top view of still another form of barrel-catch; Fig. 6, a vertical cross-section along the line A A in Fig. 3; Fig. 7, a bottom view of still another form of catch; Fig. 8, a horizontal section through rear end of barrel-lever; Fig. 9, a vertical cross-section along the line B B in Fig. 12 of the revolver-frame and barrel-lever; Fig. 10, a vertical cross-section of another form of barrel-lever; Fig. 11, a top view of a different form of strap; Fig. 12, a side view of revolver, showing method of operation; and Fig. 13, a longitudinal section through another form of barrel-catch.

Similar numbers refer to similar parts throughout the several views.

In addition to the illustrations necessary to explain clearly the nature of my invention I have added others, showing some of the variations which may be made in the details of construction, in order that it may be clearly understood that I do not confine myself to the precise details of construction shown, but hold myself at liberty to make such changes as fairly come within the spirit and scope of my invention.

The more distinctive feature of my inven-

tion is, first, in suitably forming the forward end 6 of the revolver-frame 18, Fig. 3, to act as the interior member of the breakdown hinge instead of, as heretofore, the exterior, whereby the outside barrel-levers 7 (see Fig. 1) may act not merely as strengthening members to the revolver, but also as the outside members of the breakdown hinge, barrel-levers being thus provided with a minimum additional weight of metal to the revolver as a whole, in which event the breakdown hinge may be materially reduced, as in diameter, (see dotted lines 36, Fig. 12,) the extractor-cam 5, Fig. 3, if used, being placed in the suitably-slotted end 6 of the revolver-frame 18, as shown more clearly in Fig. 6, instead of within the barrel, as heretofore; second, a horizontal thumb-ridge 2, Fig. 1, along the finger-face 3 of the barrel-catch 1, (see also Figs. 4, 7, and 12,) in combination with a thumb-recess 15, Fig. 3, in the revolver-frame to the rear of the recoil-plate 19, whereby the thumb 20, Fig. 12, of the revolver-hand, presented necessarily from below, will readily and with certainty engage the said barrel-catch at will, in order that it may be lifted, and the same may be disengaged from the catch-posts without assistance from the free hand. The rear ends of the barrel-levers, as 7, Fig. 1, have on the outside knobs 8, (see also Fig. 8,) projecting beyond the barrel-frame, as shown by the dotted lines 18', Fig. 8, whereby the said barrel-levers may be readily loosened, as by a blow, should they become rusted in place or the barrel pushed forward by the finger after the thumb has lifted the catch. In order to reduce the surface of the revolver-frame in contact with the lever-arm to reduce the bad effects of rusting, there being little wear, a recess 17, Fig. 3, in the said surface of the revolver-frame may serve to this end, as well as to contain lubricating matter. In the same way the barrel-levers, as 7", Fig. 10, may be recessed inside or outside, or both, thus reducing weight without materially reducing strength. The extractor-cam may be similarly recessed or perforated. The two outside barrel-levers 7", Fig. 9, may be connected by a horizontal web 26, the two recesses 17 being formed in either side of the frame 18, or the rear end of the barrel-lever may have a downwardly-projecting hook 29,

Fig. 12, engaging with a similar recess in the barrel-frame to reduce the strain on the breakdown pivot in the case of a blow.

Where the breakdown hinge is so constructed that the barrel 14, Fig. 1, must be slid forward away from the recoil-plate 19 (see Fig. 3) before being depressed, a spring 9, Fig. 1, to be within the revolver-frame, preferably, assists the said forward motion, while the catch-posts 4, Figs. 2 and 4, may be made slanting upward to the rear in whole or in part, (see dotted lines 4'), so that a simple rearward motion of the barrel will automatically lift the barrel-catch.

In combination with a thumb-ridge 2, Fig. 1, extending around the finger-face 3, is preferably used the barrel-catch spring 24, Fig. 13, held in place by the screw 23, both within a suitable recess 22 within the strap 16, the said spring bearing upon a suitable projection or lip 25 on the forward part of the barrel-catch 1'', and thus serving to automatically return the said catch to its place; or the barrel-catch may have in addition two forward portions 21, Fig. 7, through which the barrel-catch pin 27 also passes, thus giving maximum strength with less binding of parts; or the thumb-ridge 2'', Fig. 4, may extend downwardly over the finger-face, so as to replace the latter, or the thumb-ridge may be placed at the bottom of the finger-face (see 2'', Fig. 4) or at some intermediate point; or the thumb-ridge may extend forward, as in Figs. 5 and 12, instead of to the rear, as in Fig. 1; or the thumb-ridge 2 and finger-face 3, Fig. 12, may be parallel with the adjacent side face of the strap 16, the said thumb-ridge being preferably checked. The said thumb-recess, however, alone will enable the thumb when presented from below to engage with the usual form of catch fairly well. A rib 28, Figs. 11 and 12, may serve to strengthen the connection of the strap 16 to the barrel 14.

The revolver being held in the right hand, the barrel-catch of breakdown revolvers has heretofore been usually lifted by being grasped between the thumb—as shown by dotted lines in Fig. 12—and forefinger of the left hand, the left hand then depressing the barrel, the shells being extracted through the resulting action of the extractor-cam, when cartridges must first be sought with the left hand before they can be inserted and the revolver closed ready for firing; but with suitable thumb-ridge 2, Fig. 12, and thumb-recess, as aforesaid, the left hand may hold cartridges in readiness until the first round is fired, when the thumb 20 of the revolver—usually the

right-hand may be presented from below against the said thumb-ridge, the said recoil-plate 19 acting as a guide, and the barrel-catch thus lifted from its engagement with the catch-posts. The barrel in the meantime having been placed, say, against the back of the hips a movement of the revolver-arm will 65 depress the barrel, and thus extract the shells, gravity assisting instead of, as heretofore, tending to retard the complete extraction, when cartridges already held in readiness by the left hand may be quickly inserted.

I am aware that prior to this application rearward extensions of the barrel underneath the cylinder have been claimed by myself and that barrel-catches pivotally connected with the strap have long been known. I therefore 75 do not claim these broadly herein; but

What I do claim as my invention, and desire to secure by Letters Patent, is—

1. In a breakdown revolver, the combination, substantially as hereinbefore set forth, of the revolver-frame, the forward end of which is suitably shaped to act as the interior member of the breakdown hinge, and suitably slotted to receive the extractor-cam, together with the barrel and outside recessed webbed barrel-levers, the said outside recessed webbed barrel-levers being suitably fashioned or formed to act as the exterior members of the breakdown hinge, and having on their rear ends suitable projections; all of which whereby a breakdown revolver may be provided with outside barrel-levers, with a minimum increase of weight, which said levers may be readily loosened from their seat in the revolver-frame, as by a tap upon said projec- 95

2. In a breakdown revolver, the combination, substantially as hereinbefore set forth, of the thumb-recess in the frame of the revolver, to the rear of the recoil-plate, and the thumb-ridge along and around the finger-face of the barrel-catch, together with the barrel-catch spring 24, bearing upon a suitable lip 25 upon the barrel-catch, whereby a strong, simple, and durable barrel-catch, which may 105 be readily and with certainty lifted by the thumb of the revolver-hand, is provided, all substantially as set forth.

In testimony whereof I have signed my name to this specification in the presence of 110 two subscribing witnesses.

AUDLEY H. STOW.
